UNITED STATES PATENT OFFICE.

GEORGE A. BUSCH AND WILLIAM SCHMIDT, OF LOUISVILLE, KENTUCKY.

WAISTBAND FOR TROUSERS.

Application filed September 16, 1922. Serial No. 568,687.

To all whom it may concern:

Be it known that we, GEORGE A. BUSCH and WILLIAM SCHMIDT, citizens of the United States, residing at Louisville, in the county of Jefferson, State of Kentucky, have invented a new and useful Waistband for Trouser, of which the following is a specification.

This invention has reference to fasteners of the separable type especially designed for use in connection with trousers, the primary object of the invention being to provide a fastener of this character wherein one section will move with respect to the other section, upon movement of the supporting waist band used for supporting the trousers.

Another object of the invention is to provide a device of this character which although permitting movement of one section with respect to the other section will maintain the trousers in their proper positions.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is an elevational view disclosing trousers as supplied with a fastener constructed in accordance with the present invention.

Figure 2 is a sectional view on line 2—2 of Figure 1.

Figure 3 is a plan view of the keeper section of the fastener.

Figure 4 is a front elevational view of one section of the fastener.

Figure 5 is an elevational view looking at one edge of the section.

Figure 6 is a front elevational view of a modified form of fastener.

Figure 7 is an elevational view at one edge thereof.

Figure 8 is a plan view of a modified form of keeper section.

Figure 9 is a sectional view disclosing the relation between the portions 13' and keeper section.

Referring to the drawing in detail, the reference character 5 designates the waist band of trousers to which the keeper 6, forming a part of the fastener is secured. This keeper embodies a base plate 7 provided with openings 9 to receive threads, by means of which the base may be secured to the trousers, the spur 9 forming a part of the base, being designed to pierce the cloth material of which the trousers are formed to further secure the base in position.

Formed integral with the base 7 is an extension 10 which is adapted to be bent over the base 7 and lie in spaced relation therewith, the extension 10 being formed with an elongated opening 11 and formed with a circular opening 12 adjacent to one end thereof. Cooperating with the extension 10 is a fastener section indicated at 13 which includes a bar formed with lateral extensions 14 at the ends thereof, the lateral extensions being provided with cut out portions 15 defining spurs 16.

Secured to this section 13 is a headed pin 17 which head is of a diameter to fit within the opening 12 to secure the sections of the fastener, the pin being designed to move in the opening 11 so that when the waist line of the trousers is shortened, movement of the sections of the fastener, with respect to each other will be permitted, to prevent bulging of the trousers at the waist line.

When the sections of the fastener are moved into cooperative relation with each other, the head of one section which is received by the opening of the adjacent section, may assume various positions throughout the length of the elongated opening of the opposed section.

As shown by Figures 6 and 7 of the drawings, one of the fastener sections includes a bar 18 bent intermediate its ends to provide a head 19 to be fitted in a correspondingly shaped keeper 20 formed intermediate the bar 21 of the keeper section 22. This section 22 is also formed of lateral extensions 23 which may be positioned between layers of cloth of which the waist band is formed to secure the keeper section 20 against movement.

The bar of each fastener section is formed with right angled portions 13' that support the bar in spaced relation with the surface to which the fastener section is secured, at

the same time these angular portions engage the side edges of the keeper section associated therewith to restrict lateral movement of the sections with respect to each other.

5 From the foregoing it will be seen that due to the construction of the keeper section as shown by Figure 8 of the drawing, the member 19 may be brought into engagement with either the bar 21 or the bar 24 to provide an adjustable waist band for trousers.

Having thus described the invention, what is claimed as new is:

1. In a separable fastener, a keeper section including a base plate, an extension formed integral with the base plate, said extension having an elongated opening, a fastener section, said fastener section including a shank and a head, and right angled portions formed adjacent to the ends of the fastener section, said right angled portions adapted to engage the side edges of the extension of the keeper section to restrict lateral movement of the fastener section, and said head

adapted to move in the elongated opening of the extension.

2. In a separable fastener, a keeper section including an extension formed with an elongated opening, a fastener section including a bar, a pin having a head carried by the bar, said pin adapted to move into the elongated opening to secure the keeper section and fastener section, and means forming a part of the fastener section and adapted to cooperate with the side edges of the keeper section to restrict lateral movement of the sections with respect to each other.

30 In testimony that we claim the foregoing as our own, we have hereto affixed our signatures in the presence of two witnesses.

GEORGE A. BUSCH.
WILLIAM SCHMIDT.
